UNITED STATES PATENT OFFICE.

WILLIAM T. FERGUSON, OF BECKLEY, WEST VIRGINIA.

MINE DOOR.

Application filed July 29, 1922. Serial No. 578,334.

To all whom it may concern:

Be it known that I, WILLIAM T. FERGUSON, a citizen of the United States, residing at Beckley, in the county of Raleigh and 5 State of West Virginia, have invented certain new and useful Improvements in Mine Doors; and I do hereby declare the following to be a full, clear, and exact description of the invention, such as will enable others 10 skilled in the art to which it appertains to make and use the same.

The invention relates to means whereby the ventilation of a mine is controlled to prevent dangerous accumulation of gas and to 15 insure a positive circulation of air and which results are attained by the use of doors or stops.

Specifically considered, the present invention relates to an automatic mine door 20 adapted to be actuated by means of a trip rail disposed adjacent the track upon which the mine cars run so as to be engaged by the car wheels, the door being automatically opened by the car or other moving object 25 and automatically closed by means of a spring or weight or their combined action.

Other objects and advantages will be apparent and suggest themselves as the nature 30 of the invention is understood.

While the drawings illustrate an embodiment of the invention it is to be understood that in adapting the same to meet different conditions and requirements, various changes 35 in the form, proportion and minor details of construction may be resorted to without departing from the nature of the invention.

Referring to the accompanying drawings forming a part of the application,

Figure 1 is a diagrammatic view of an 40 automatic mine door embodying the invention, showing the same applied,

Figure 2 is a side view of the parts illustrated in Figure 1,

Figure 3 is an enlarged sectional detail on 45 the line 3—3 of Figure 1,

Figure 4 is an enlarged detail of the parts associated with the hinge joint between sections of the trip rail,

Figure 5 is an enlarged sectional detail 50 on the line 5—5 of Figure 1,

Figure 6 is a side view of the parts shown in Figure 5, and

Figure 7 is an enlarged view of the buffer 55 or yieldable connection interposed in the line of connections.

Corresponding and like parts are referred to in the following description and designated in the several views of the drawings by like reference characters.

The numeral 1 designates the rails comprising the track upon which the mine cars are adapted to run. At the required point in the length of the track, a frame 2 is erected to receive the mine door which 60 contacts therewith. As shown, the mine door is of the type comprising similar leaves 3 hinged at their outer vertical edges to the uprights of the frame 2 so as to swing in opposite directions. A transverse bar 4 is 65 pivotally connected to arms 5 projecting laterally from the leaves 3, whereby to cause said leaves to move in unison in reverse direction. A curved arm 6 projects laterally from the hinged portion of each of the leaves 75 3 and a link 7 is pivotally connected to the outer portion of each of the arms 6. One of the arms 6 has an extension 8 to which a contractile helical spring 9 is adjustably connected by means of a turnbuckle 10, whereby 80 the door is normally held closed and the tension of the closing spring adapted to be regulated.

A trip rail is associated with each track rail 1 and is preferably disposed along the inner side of the track rail, there being a trip rail for each approach to the door, whereby the latter may be automatically 85 opened by a car approaching from either 90 direction. Each of the trip rails comprises an outer section 11 and an inner section 12, the adjacent ends of the two sections being hingedly connected as indicated most clearly 95 in Figure 4. The trip rail is of L-form in cross section and a hinge 13 is attached to the horizontal portion of the adjacent ends of the sections 11 and 12. A fitting 14 is riveted or otherwise attached to one of the members of the hinge 13 and the upper end 100 of a link 15 is pivotally connected thereto. The lower end of the link 15 is pivoted to the outer end of an arm 16 which is attached to a shaft 17. A weighted arm 18 is attached to the shaft 17 and materially assists in the 105 operation of the door. An arm 19 attached to the shaft 17 is disposed approximately at a right angle to the arm 16 and has a rod 20 connected thereto. Other shafts 17^a and 17^b are disposed upon opposite sides of the shaft 17 and are mounted in a like manner thereto 110 and are provided at their outer ends with

arms 19^a and 19^b, respectively, to which the rod 20 is pivotally connected. A bar 21 passes beneath a track rail 1 and is attached thereto and the shaft 17 or corresponding part is journaled thereto. The bar 21 is of L-form in cross section and is firmly attached to the foot of the track rail. A plate 22 is attached to the inner end of the bar 21 and one end of the shaft 17 is journaled thereto. The plate 22 has a lip 23 which underlaps the lower edge of the vertical wing of the bar 21. A plate 24, attached to the horizontal wing of the bar 21, overlaps the foot of the rail 1 at one side of the web thereof. A bolt 25 secures the bar 21 to the foot of the rail 1 upon the opposite side of the web thereof. This is shown most clearly in Figure 3.

A fulcrum block 26 is secured to a track rail 1 and is formed in its outer end with a dovetail slot 27 in which is loosely fitted a dovetail fulcrum 28 riveted or otherwise secured to the underside of the trip rail section 11. A bolt 29 extends across the dovetail slot 27 and retains the dovetail fulcrum 28 in position therein. The fulcrum block 26 has an extension 30 which passes beneath the rail 1 and is bolted or otherwise attached thereto. A portion of the fulcrum block 26 overhangs the foot of the rail as indicated at 31, thereby materially assisting the fastening means in holding the fulcrum block in position. The fulcrum 28 has a loose fit in the slot 27, as shown most clearly in Figure 6, whereby to admit of a rocking movement thereof as the section 11 pivots. The arrangement is such as to provide a substantial joint and admit of the ready removal and replacement of the trip rail as required.

The trip rail section 11 inclines to the horizontal, whereas the section 12 is horizontally disposed. A mine car approaching the door rides upon the section 11 and depresses the trip rail whereby the several shafts 17, 17^a and 17^b are rocked with the result that the rod connecting the arms of said shafts with one another and with the arm 6 of the mine door is moved longitudinally and effects an opening of the door against the action of the weighted arm 18 and spring 9. After the car clears the door and the trip rail upon the opposite side thereof, said door is automatically closed by the combined action of the spring 9 and weighted arm 18. It is observed that the operating parts are attached directly to the track rails and not to any ties or other supporting

means, hence in the installation of the mine door, it is not necessary to adapt the supporting and connecting means to certain ties or to provide special supporting means, and as a result the door may be quickly installed and at a minimum expense.

To prevent impairment of the connections by sudden depression of the trip rail, a buffer or yieldable connection 32 is interposed in the line of connections. This buffer comprises a guide frame 33, a cross head 34 slideable on the guide frame and an expansible helical spring 35 mounted on an end portion of a connecting rod and confined between the cross head 34 and an end of the frame 33.

What is claimed is:

1. In a mine door, operating means therefor including a trip rail carrying a fulcrum, a fulcrum block in which said fulcrum is disposed with sufficient play for actuation and means for attaching the fulcrum block directly to a track rail.

2. In a mine door, operating mechanism therefor including a trip rail provided with an approximately dovetail fulcrum, a fulcrum block having a slot to receive the fulcrum of the trip rail, means for closing said block to retain the fulcrum in place therein, and means for attaching the fulcrum block directly to a track rail.

3. In a mine door, operating mechanism therefor including a trip rail having a dovetail fulcrum, a fulcrum block having an extension adapted to pass beneath a track rail and to be attached to the foot thereof upon one side and having a portion overhanging the foot upon the opposite side, said block having a dovetail slot to receive the fulcrum of the trip rail, and means for closing said slot to retain the fulcrum therein.

4. In a mine door, operating mechanism therefor including an L-bar passing beneath a track rail, means for attaching the bar to the foot of the rail upon one side, a plate forming connecting means between said bar and the foot of the rail upon the opposite side, a plate attached to the vertical wing of the bar and having a lip underlapping the lower edge of said wing, a shaft mounted upon said plate and bar, and connecting means between said shaft and mine door.

In testimony whereof, I affix my signature in presence of two witnesses:

WILLIAM T. FERGUSON.

Witnesses:

C. V. COTTLE,
